UNITED STATES PATENT OFFICE

GORDON E. STARR, OF LOS ANGELES, CALIFORNIA

DESIGN FOR A DECORATIVE SEA SHELL

Application filed September 22, 1931. Serial No. 41,180. Term of patent 3½ years.

To all whom it may concern:

Be it known that I, GORDON E. STARR, a citizen of the United States of America, and a resident of the city of Los Angeles, in the county of Los Angeles and State of California, have invented a new, original, and ornamental Design for Decorative Sea Shells, of which the following is a specification, reference being had to the accompanying drawings, forming part thereof.

Figure 1 is a front elevation of a decorative sea shell showing my new design; and Figure 2 is a top plan view thereof on a reduced scale, the base as shown in Fig. 1 being obscured.

I claim:

The ornamental design for a decorative sea shell as shown and described.

GORDON E. STARR.
